UNITED STATES PATENT OFFICE

FRANK B. DAVIDSON, OF MARSEILLES, ILLINOIS, ASSIGNOR TO HOWE AND DAVIDSON COMPANY, OF MARSEILLES, ILLINOIS, A CORPORATION OF NEW JERSEY.

CONTAINER OR CADDY.

1,134,998.

Specification of Letters Patent. Patented Apr. 13, 1915.

Application filed November 16, 1912. Serial No. 731,694.

To all whom it may concern:

Be it known that I, FRANK B. DAVIDSON, a citizen of the United States, and a resident of Marseilles, in the county of La Salle and 5 State of Illinois, have invented certain new and useful Improvements in Containers or Caddies; and I do hereby declare that the following is a full, clear, and exact description thereof, reference being had to the accompanying drawings, and to the letters of 10 reference marked thereon, which form a part of this specification.

This invention relates to a novel box or container made from heavy paper-board, 15 straw-board, or like material and designed more especially to be used in place of a sheet metal box or "caddy" for containing crackers, biscuits, or like bakery goods, as well as other articles of merchandise in bulk, and 20 which is adapted for use both in shipping such articles to the retail merchant and as a receptacle in which the articles may be kept while in the shop of the retail merchant and from which the articles may be conveniently 25 removed from time to time when delivered to the customer.

One object of the invention is to provide a construction in such boxes or containers, 30 by which the same may be made from a piece or blank of sheet material so formed and prepared by the manufacturers thereof, that the boxes or containers may be folded flat for shipment, and set up in form for 35 use, or the insertion of their contents, by the manufacturer of the articles with which they are to be filled.

Another object of the invention is to provide a construction in such boxes or containers by which the same may be conveniently 40 provided with a panel of glass or other transparent material through which the crackers, biscuits, or other articles contained therein may be seen, and the character thereof observed, without opening the 45 box or container.

The invention consists in the matters hereinafter set forth and pointed out in the appended claims.

In the accompanying drawings—Figure 1 50 is a perspective view of the improved box or container, set up in readiness for use; Fig. 2 is a perspective view of the bottom or lower end of the container, showing the flaps constituting said bottom in partially folded position; Fig. 3 is a sectional view of the con-

tainer, taken on a vertical plane extending from front to rear of the same; Fig. 4 is a cross section of the container, taken on line 4—4 of Fig. 3; Fig. 5 is a plan section, taken on line 5—5 of Fig. 4; Fig. 6 is a view of 60 the bottom of the container with a part of the sealing strip broken away to show the construction of the flaps constituting the bottom wall thereof; Fig. 7 is a view of the blank from which the container is made; 65 Fig. 8 is a view of the bottom of the container showing the inner flaps folded inwardly and the outer flaps in extended position.

The body of the box or container embodying my invention is of tubular form and is preferably made from a single piece or blank (shown in Fig. 7), which is bent in the form of a tube, and the ends of which are secured to each other by paste, glue or 70 other fastening means.

The tubular body of the box is shown as consisting of four connected upright walls A, A', A², A³, provided at their lower ends with flaps B, B', B², B³, which are folded 80 together to constitute the bottom wall of the box. In the particular box shown the wall A constitutes the front wall, the wall A² the rear wall, and the walls A', A³, the side walls of the box. The top wall C of the 85 box has the form of a lid or cover which is flexibly connected at its rear margin with the rear wall A² of the box and is preferably made integral with said rear wall. Said lid or cover C is shown as provided with marginal flanges c, c, c, on its side and forward margins, adapted to fit over the upper margins of the front wall A and side walls A', 90 A³ of the box.

Now referring to the construction of the flaps which form the bottom wall of the box, two of the same, to-wit, B', B³ constitute extensions of the opposite side walls A', A³, and are made of such length as to overlap each other when the same are folded inwardly into the plane of the bottom wall. Said flaps have parallel side margins, and the width of the same is substantially equal to that of the side walls A', A³, to which said flaps are attached. One of said flaps, B³, is provided in its end margin with a notch, generally of rectangular form, having an inner margin b which is parallel with the end margin of the flap, and lateral margins b', b', which are parallel with the side 100

105

110

5 margins of the flap. The opposite flap B' is provided on its end margin with a projecting portion or tongue B⁴, which is generally of rectangular form, provided with
 10 an end margin b² parallel with the end margin of the flap and with lateral margins or shoulders b³, b³, which are parallel with the side margins of the flap. The inner margin b of the notch in the flap B³ is so arranged
 15 as to be approximately in line with the end margin of the main part of the flap B' when said flaps are folded together, so that the tongue B⁴ will extend over or overlap the body of the flap B³ inside of the inner margin b of the notch. The width of said notch is, moreover, substantially equal to that of the tongue B⁴ so that when the said flaps B' and B³ are folded together, the side margins or shoulders of the notch and tongue will
 20 engage each other in such manner as to hold the meeting ends of the two flaps from moving or shifting laterally with respect to each other. The contact of the end margin of the flap B', at the sides of the tongue, with the ends of the margin b of the notch, also
 25 serves to hold the said flaps B' and B³ from movement toward each other, and thereby aids in holding the lower margins of the side walls A' and A³ from being collapsed or forced inwardly by external pressure thereon.

30 The flaps B', B³ on the side walls are first folded inwardly, in the folding of the flaps constituting the bottom wall, and the same will be hereinafter called the inner flaps. The flaps B, B², which are attached to the front and rear walls of the box, are folded inwardly outside of the said inner flaps and will be hereinafter called the outer flaps.
 35 40 Said outer flaps B, B² are both made of substantially the same length and have inclined or oblique side margins b⁴, b⁵, which give, in general, a tapered form to the said outer flaps, which are narrower at their outer than at their inner ends. At their outer ends, said outer flaps are laterally notched to provide extensions B⁶, B⁶, arranged in opposite relation to each other, so that their inner margins meet each other edge to edge, when the said flaps are interfolded. Said extensions are provided with laterally extending, and oppositely disposed locking tongues b⁶, b⁷. The said locking tongues are, moreover, located at a distance outwardly from the end margins b⁸, b⁹, of said outer flaps, so that notches, at least equal in width to the width of the locking tongues, are formed between the said tongues and the margins b⁸, b⁹. Said end margins b⁸, b⁹, are, moreover, so disposed as to substantially meet or abut against the corresponding end margins b¹⁰, b¹¹ of the extensions B⁶, B⁶ on said outer flaps. When said outer flaps are folded together, the tongues b⁶, b⁷, are inserted laterally beneath the inner margins
 45 50 55 60 65

of the extensions and the tongues on the two flaps are engaged with each other, edge to edge, at their inner margins so as to lock the outer flaps from spreading apart.

From the construction described it will be understood that when the inner flaps are folded inwardly and in substantially the same plane, their parallel side margins will bear against, and thereby serve to support and hold from inward bending or flexure, the lower margins of the front and rear walls A, A² of the box. Moreover, by reason of the fact that the inner flaps meet or overlap at their end margins and the outer flaps engage or bear against the side margins of said inner flaps, said outer flaps when folded inwardly over the inner flaps and interlocked, will support or sustain said inner flaps against the effect of downward pressure acting on the inner flaps in a direction to force or press the same downwardly or outwardly. It follows from the above that the inner flaps, constructed as described, in connection with the interlocking outer flaps, afford a very strong and rigid construction in the bottom wall of the box. The interlocking of the tongue and notch on the inner flaps acts to hold the bottom part of the box from distortion under pressure coming on its diagonally opposite corners, and also to resist inward bending or flexure of the lower parts of the side walls A' and A³. Moreover, the engagement of the side margins of said inner flaps with the outer flaps, as well as the interlocking of the said inner flaps with each other at the central parts of the same, affords rigidity in the bottom wall by which it is adapted to resist downward pressure due to the weight of the contents of the box.

100 105 110 115 120 125 130 For the purpose of holding the inner and outer flaps in contact with each other, when folded inwardly and interlocked as described, and to add strength and rigidity to the bottom wall of the box, a sealing or closing strip D, (Figs. 3, 4 and 6) of flexible material, such as tough paper, is applied across the bottom wall and secured by adhesive material to the outside surfaces of both the inner and outer flaps; the end portions of said strip being brought into contact with and secured to the parts of the inner flaps exterior to the tapered side margins of the outer flaps. Said sealing strip is shorter in length than the distance between the side walls of the box so that its ends terminate within the side margins of the bottom and do not extend upwardly upon or over the side walls of the box, which will usually be decorated or ornamented so as to give an attractive appearance to the box.

The flanges c, c, c on the lid or cover of the box are formed by integral, folded flaps thereon, secured together at the front corners of the cover by means of tongues or

flaps c' , c' on the front flange, which are folded over the adjacent ends of the side flanges and secured thereto by metal fasteners or rivets c^2 , c^2 .

5 As a further improvement in boxes or containers made of flexible sheet material and adapted for the purposes stated, I provide in one of the walls thereof, preferably the front wall A, a removable panel E 10 formed by a portion of the wall itself, which is partially severed at or around its margins from the said wall in such manner that it may be easily detached therefrom. As shown, the panel E is partially severed from 15 said wall A by means of a plurality of slits e , e (Fig. 4) so constructed as to leave between their ends short connecting members e' , e' , sufficient in number to suitably support the panel. Said connecting members 20 may be easily cut through by a knife or other implement when it is desired to remove the panel from the box. The opening left by removing the panel will, during the use of the box, be covered by a sheet F of 25 transparent material, such as glass, transparent celluloid, or the like. Such transparent sheet F will be made somewhat larger than the opening formed by the removal of the panel and will be applied 30 against the inner face of the wall in which said opening is formed.

The sheet F of transparent material, so applied to cover the opening formed by removal of the panel E, may be secured to 35 the wall of the box in any desired manner, but, as a further improvement, I provide a construction especially adapted for use where the panel is located near the bottom wall of the box, as follows: The inner flaps 40 B', B³ of the bottom wall, are provided at their side margins, adjacent to the front wall A with narrow extensions or flaps B⁷, B⁸, adapted to be folded upwardly to form flanges on the flaps, and which, when the 45 box is set up or completed, are located in a position parallel with and inside of the lower portion of said front wall A. The flaps thus arranged serve as a means of holding or securing the lower margin of the 50 transparent sheet against the said front wall, said lower margin of the transparent sheet being inserted at its lower edge between the lower part of the front wall and said flanges. When the lower margin of 55 the transparent sheet is thus held by flanges on the inner flaps of the bottom wall, its upper margin may be confined or held by means of a strip G (Figs. 3 and 4) of tough paper, or other like material, secured by 60 adhesive material to the inner face of the wall and overlapping or extending over the marginal part of the transparent sheet above the opening formed by the detachment of the removable panel.

65 In preparing the box for the insertion of

its contents, the removable panel E is left in place and the transparent sheet F is applied over the panel and secured in place, as described. The box will then be filled and its top closed. The box will be shipped 70 in this condition to the retail merchant. In so shipping the box, it will usually be placed within an outside box or container, so as to protect the box from injury, or defacement, such as would be detrimental to its 75 appearance when upon the grocer's shelves, or when in use in a retail shop. When the filled box is received by the retail merchant the latter will entirely remove or detach the panel E, so that the contents of the box 80 will be visible through the transparent sheet in the same manner as in the case of the similar metal boxes which have heretofore been usually provided with openings covered by attached glass panels, for the 85 same purpose. It will of course be understood that the removable panel E will be left in its original position during the shipment of the box, and will thus serve to protect the glass or transparent sheet from 90 breakage or injury in transit and until the box reaches the hands of the retail merchant.

The blank from which the box embracing the features above described is preferably made, consists of a single piece of paper-board, straw-board, or other like material, as shown in Fig. 6. As is clearly illustrated in this figure, the four sections A, A', A², A³, corresponding with the correspondingly lettered walls of the box, form a single elongated piece or blank, having on the side margin of the section A' a flap A' adapted to be secured to the meeting margin of the section A² at the opposite end of 100 the blank, as seen in Fig. 5, to give tubular form to the body of the box. The folding top or lid C constitutes an integral extension of the wall A², while the inner and outer bottom flaps B, B', B², B³ constitute 105 extensions of the sections A, A', A², A³. The said top or lid C is provided with integral flaps c, c, c adapted to form the front and lateral flanges on said top, and one of 110 said flaps is provided with tongues c', c', 115 as heretofore described. The parts upon the several flaps, by which the interlocking of the said flaps is accomplished are, in the view of the blank (Fig. 7), lettered to correspond with the parts shown in the other 120 figures of the drawings. When the blank has been made into tubular form, as described, it may be collapsed into flat form by the flexing of the blank at the diagonally opposite corners of the body; the several 125 flaps on the blank being allowed to remain in their extended or unfolded positions. In this condition the blank may be shipped by the manufacturer thereof to the maker of 130 the articles to be packed therein, with the

usual advantages gained by shipment of boxes or cartons in "knock-down" form. The blanks may be easily set up for use, and the transparent sheets inserted therein, 5 as hereinbefore described.

While the removable panel E is shown as located at the lower part of the front wall A of the box and in the correspondingly lettered section of the blank, yet such a removable panel may be located in one of the other walls of the box or elsewhere on the blank, as may be desired or preferred.

If desired, adhesive material may be applied between the meeting faces of the inner and outer flaps and in that case the sealing strip will not be alone relied upon to aid in giving stiffness and rigidity to the bottom wall of the box. Whether the inner and outer flaps are so additionally held in place by adhesive material or not, the presence of the sealing strip serves to close or seal the bottom wall of the box in a manner to prevent the entrance of insects and to avoid the liability of escape of small particles from the interior of the box.

A carton embodying the features of construction set forth may be variously modified with respect to its details, and I do not, therefore, desire to be limited to the specific construction illustrated except as pointed out in the appended claims.

I claim as my invention—

1. A container, made of heavy paper-board or the like and having connected side walls and a bottom wall, the latter comprising two inner flaps folded inwardly and adapted to overlap each other at their end margins, and two outer flaps folded inwardly against said inner flaps; said inner flaps being provided, one with a notch, and the other with a tongue, said tongue being made of the same width as and adapted to enter said notch, the tongue projecting past the inner margin of the notch and overlapping the body of the adjacent inner flap inside of the inner margin of said notch, with the end margin of the inner flap at the sides of the tongue in contact with the ends of the inner margin of said notch, when said inner flaps are interfolded, and said notch and tongue being provided with parallel, lateral margins forming shoulders adapted to engage each other to hold said inner flaps from relative lateral movement; said outer flaps being provided with interlocking parts adapted to hold said outer flaps against said inner flaps.

2. A container, made of heavy paper-board or the like and having connected side walls and a bottom wall, the latter comprising two inner flaps folded inwardly

and adapted to overlap each other at their inner margins, and two outer flaps folded inwardly against said inner flaps, said inner flaps being provided, one with a notch, and the other with a tongue made of the same width as and adapted to enter said notch; the tongue projecting past the inner margin of the notch and overlapping the body of the adjacent inner flap inside of the inner margin of said notch, when said inner flaps are interlocked, said outer flaps being provided with oppositely disposed extensions, the lateral margins of which are parallel with each other, said extensions being provided with laterally disposed locking tongues separated from the end margins of said outer flaps by locking notches, the locking tongues being adapted to enter said locking notches and overlap the adjacent extensions, with the end margins of said extensions abutting against the end margins of said outer flaps, when said outer flaps are interlocked.

3. A container, made of heavy paper-board or the like having connected side walls and a bottom wall, the latter consisting of two inner flaps folded inwardly and adapted to overlap each other at their end margins, and two outer flaps folded inwardly against said inner flaps, said inner flaps being made of the full width of the side walls to which they are attached, and said inner flaps being provided, one with a notch, and the other with a tongue made of the same width as and adapted to enter said notch, said tongue projecting past the inner margin of the notch and overlapping the body of the adjacent flap inside of the inner margin of said notch, when the inner flaps are interfolded, said outer flaps having laterally inclined side edges, giving tapered form thereto, and being provided with oppositely disposed extensions, and on the adjacent side margins of said extensions with laterally disposed locking tongues, adapted to have endwise engagement with each other and to overlap the adjacent extensions on said outer flaps, when said outer flaps are interfolded, and a strip of flexible material adhesively secured to the outer flaps and to those portions of the inner flaps exterior to the inclined side margins of said outer flaps, thereby connecting all of said flaps.

In testimony, that I claim the foregoing as my invention, I affix my signature in the presence of two witnesses, this 4th day of November A. D. 1912.

FRANK B. DAVIDSON.
